ALUMINUM JALOUSIE DOOR ASSEMBLY

Victor E. Anderson, Bradenton, Fla., assignor to V. E. Anderson Manufacturing Company, Bradenton, Fla., a corporation of Kentucky

Application December 23, 1954, Serial No. 477,357

8 Claims. (Cl. 189—46)

The invention relates to metallic door constructions and more particularly to a door including a jalousie section. It is the object of the invention to obtain a construction comprising an assembly of extruded members which, without machining, interfit each other. It is a further object to include in this assembly a frame for the jalousie. With these objects in view the invention consists in the construction of certain elements of the door and the assembly of the same as hereinafter set forth.

In the accompanying drawings:

Fig. 1 is a front elevation of a portion of the door, including one of the stiles with portions of the cross members secured thereto.

Fig. 2 is a vertical section on line 2—2, Fig. 1.

Figs. 3, 4 and 5 are horizontal cross sections, respectively, on lines 3—3, 4—4 and 5—5, Fig. 1.

Fig. 6 is a section similar to the lower portion of Fig. 2 showing a slight modification thereof.

Fig. 7 is an enlarged vertical sectional view through the joint between the top rail of the jalousie frame and the top rail of the door.

Fig. 8 is an enlarged vertical sectional view through the joint between the bottom rail of the jalousie frame and the intermediate rail of the door.

As above described, the door is formed from extruded members, preferably of aluminum alloy, and fashioned to interfit each other without the necessity of machining operations. These members include stiles or the vertical rails of the door frame and a plurality of cross rails interfitting said stiles. In addition there are the members for forming the jalousie frame, these also interfitting members of the door frame. The stile A is formed of an extruded member of generally U-shaped cross section having front and rear side portions A' and A² and a connecting portion A³ which forms the edge of the door. The inner faces of the side portions A' and A² have integral bearing strips A⁴ and A⁵ which project inward beyond the surface of the intermediate portion A⁶. Each strip portion A⁵ also has a longitudinal groove A⁷ therein. The stiles for the hinged and swinging edges of the door are the same in construction but the latter only is illustrated in the drawings. B is the top or head rail of the door and C the bottom rail adjacent to the threshold and which may be termed the sill. D is an intermediate rail which as hereinafter described is below the jalousie frame. All of these rails B, C and D are hollow and substantially rectangular in cross section. The rail B includes a front and rear portion B', B², the top edge portion B³ and the bottom edge portion B⁴. The portions B' and B² are spaced to fit between the bearing strips A⁴ and A⁵ of the portions A' and A² of the stile members. Thus, the length of the member B is sufficient to extend into contact with the inner faces of the portions A³ of the stiles and form a reinforcement for the portions A' and A² thereof. The members A and B may be fastened to each other with plug type rivets. The member B is further provided with bead portions B⁵ which project outward beyond the sides B' and B² to overlap the ends of the portions A' and A² of the stile and forming rounded corners. The portions B' and B² also project downward slightly beyond the cross portion B⁴ so as to form a downwardly opening groove B⁶ between the same. The member C is generally of the

2

same construction as the member B but the front and rear sides C' and C² thereof which fit between the sides A' and A² of the member A are of somewhat greater vertical dimension than the corresponding portions of the member B. These side portions C', C² are cross connected by a horizontal web portion C³ which is intermediate the upper and lower edges thereof. The top cross portion C⁴ also includes a U-shaped central portion C⁵ and at the bottom of the portions C' and C² are beads C⁶ which underlap the bottom edges of the stile A similar to the beads B⁵ of the member B. To complete the bottom rail C there is an insertable expander member E of U-shaped cross section which extends upward to and cooperates with the web portion C³ to form a substantially box-like reinforcement for the bottom rail C. A weather strip may be secured to this member E either by engaging it with an undercut groove E' in the cross portion E² thereof, as shown in Fig. 2, or by providing a depending angle flange E³ for securing the weather strip to engage a threshold F, as shown in Fig. 6. The intermediate member D is also generally similar to the member B but its bottom cross portion D' has a reverse U portion D² centrally thereof similar to the portion C⁵ of the member C. The upper cross portion D³ has an upwardly opening groove D⁴ therein similar to the groove B⁶ in the member B and is also slightly inclined to correspond to the sill of the jalousie frame, as hereinafter described. All of these cross members B, C and D may be secured to the stiles by plug type rivets.

The door frame as thus far described has openings between the intermediate member D and the top and bottom rails B and C respectively. The space between the rails D and C is closed by a panel or so-called kick plate G, which at its lower and upper edges engages the U-shaped portions C⁵ and D² and is secured therein by a U-shaped border strip H also of U-shaped cross section and extending around all sides of the panel. As shown in Fig. 5, the opening between the side portions A' and A² of the stile is closed by a plate-like member I extending between the rails C and D and which in cross section has a U-shaped central portion I' and angle flanges I² at its ends. Each flange I² has an offset portion I³ fitting within a groove A⁷ of the stile member A. The opening between the members B and D receives a jalousie frame of the following construction:

J are side rails of the jalousie frame, which as shown in Fig. 3, has in cross section a generally U-shaped portion J' with spaced grooves J² in the cross member J³ of the U for fitting the edges of the sides A' and A² of the stile A. The outer side J⁴ of the U has a right angle flange J⁵ projecting outward therefrom and provided with an undercut groove J⁶ therein. The inner side J⁷ terminates in an angle flange portion J⁸ adapted to receive a screen frame. To secure this member J to the stile one or more nut members K of rectangular form are engaged with the grooves A⁷ in the portions A' and A² of the stile A and a clamping screw K' connects the portions J³ with said nut. Only one of these side rails is illustrated but the other is of the same construction. The top rail L of the jalousie frame is of a generally U cross-section and on the cross member L' thereof there are spaced upwardly projecting ribs or beads L² fitting in the groove or recess B⁶ in the member B and preventing relative horizontal movement between said rails B and L. A screw L³ engaging a threaded aperture in the portion B⁴ of the member B clamps the member L thereto and holds the ribs L against displacement from the groove B⁶. The front flange L⁴ of the member L has an undercut channel in its inner face for receiving a sealing strip. The bottom rail M or sill portion of the jalousie frame has similar attachment means to the cross rail D of the door frame, including spaced downwardly pro-

jecting ribs M⁵ on the underside of the bottom rail M of the frame and fitting in the groove or recess D⁴ in the intermediate rail D, and a screw M⁶ extending through the bottom rail M of the frame and threadedly engaging the cross portion D³ of the intermediate rail D. Such bottom rail M inclines downward in an outward direction at the same angle as that of the portion D³ of the rail D. At its outer end the bottom rail M has a downwardly and outwardly extending angle flange M' with an undercut channel M² in the outer face of the downwardly extending portion for receiving a sealing strip. At its inner end the bottom rail M has an upturned flange M³. The jalousie is mounted on the flanges J⁵ and as shown in Fig. 3 comprises the individual members N for holding the glass N'. Each of said members N is pivotally attached at N⁴ to said flanges J⁵ and has an operating portion N² projecting inward into the U-shaped portion of the member J. An operating bar N³ is pivotally attached to each of the members N². Thus all of the members N are simultaneously operated by the raising or lowering of the bar N³.

What I claim as my invention is:

1. A metal door structure comprising an inwardly opening channel-shaped upright stile, the inner faces of opposite sides of said channel-shaped stile being provided adjacent the mouth and adjacent the base of the channel with opposed integral bearing strips, each of the opposed strips adjacent the mouth of said channel having an inwardly opening groove therein, top and bottom horizontal rails extending into said channel-shaped upright stile between and fitting snugly against said opposed bearing strips so that said rails form reinforcements for opposite sides of said channel-shaped stile, a horizontal rail intermediate said top and bottom rails extending into said channel-shaped upright stile between and fitting snugly against said opposed bearing strips so that said rail forms a further reinforcement for opposite sides of said channel-shaped stile, opposed edges respectively of said bottom rail and of said intermediate rail having oppositely projecting opposed vertically opening channel portions, a kick plate closing the space between said bottom and intermediate rails and having its upper and lower edges within said opposed vertically extending channel portions, and a plate-like member closing the mouth of said channel-shaped stile between said bottom and intermediate rails, said plate-like member having portions within the grooves aforesaid in said bearing strips and having an inwardly projecting outwardly opening channel portion receiving the adjacent upright edge of said kick plate.

2. A metal door structure comprising an inwardly opening channel-shaped upright stile, the inner faces of opposite sides of said channel-shaped stile being provided adjacent the mouth and adjacent the base of the channel with opposed integral bearing strips, each of the opposed strips adjacent the mouth of said channel having an inwardly opening groove therein, top and bottom horizontal rails extending into said channel-shaped upright stile between and fitting snugly against said opposed bearing strips so that said rails form reinforcements for opposite sides of said channel-shaped stile, a horizontal rail intermediate said top and bottom rails extending into said channel-shaped upright stile between and fitting snugly against said opposed bearing strips so that said rail forms a further reinforcement for opposite sides of said channel-shaped stile, a frame within the space between said top and intermediate rails, said frame having an upright inwardly opening channel-shaped side rail, the base of said side rail having spaced grooves therein receiving the inner edges of said inwardly opening channel-shaped stile, and means securing said frame to said stile, including transversely extending members within said channel-shaped stile and having their opposite upright edges within the grooves aforesaid in said bearing strips, and clamping elements extending through the base aforesaid of said channel-shaped side rail and engaging said transversely extending members, opposite sides of the top rail of said door projecting downwardly beyond the bottom edge thereof and forming therewith a downwardly opening groove, opposite sides of the intermediate rail of said door projecting upwardly beyond the upper edge thereof and forming therewith an upwardly opening groove, the top rail of said frame having spaced

said channel-shaped side rail and engaging said transversely extending members.

3. A metal door structure comprising an inwardly opening channel-shaped upright stile, the inner faces of opposite sides of said channel-shaped stile being provided adjacent the mouth and adjacent the base of the channel with opposed integral bearing strips, each of the opposed strips adjacent the mouth of said channel having an inwardly opening groove therein, top and bottom horizontal rails extending into said channel-shaped upright stile between and fitting snugly against said opposed bearing strips so that said rails form reinforcements for opposite sides of said channel-shaped stile, a horizontal rail intermediate said top and bottom rails extending into said channel-shaped upright stile between and fitting snugly against said opposed bearing strips so that said rail forms a further reinforcement for opposite sides of said channel-shaped stile, opposed edges respectively of said bottom rail and of said intermediate rail having oppositely projecting opposed vertically opening channel portions, a kick plate closing the space between said bottom and intermediate rails and having its upper and lower edges within said opposed vertically extending channel portions, a plate-like member closing the mouth of said channel-shaped stile between said bottom and intermediate rails, said plate-like member having portions within the grooves aforesaid in said bearing strips and having an inwardly projecting outwardly opening channel portion receiving the adjacent upright edge of said kick plate, a frame within the space between said top and intermediate rails, said frame having an upright inwardly opening channel-shaped side rail, the base of said side rail being interlocked with the inner edges of said inwardly opening channel-shaped stile, and means securing said frame to said stile, including transversely extending members within said channel-shaped stile and having their opposite upright edges within the grooves aforesaid in said bearing strips, and clamping elements extending through the base aforesaid of said channel-shaped side rail and engaging said transversely extending members.

4. A metal door structure comprising an inwardly opening channel-shaped upright stile, the inner faces of opposite sides of said channel-shaped stile being provided adjacent the mouth and adjacent the base of the channel with opposed integral bearing strips, each of the opposed strips adjacent the mouth of said channel having an inwardly opening groove therein, top and bottom horizontal rails extending into said channel-shaped upright stile between and fitting snugly against said opposed bearing strips so that said rails form reinforcements for opposite sides of said channel-shaped stile, a horizontal rail intermediate said top and bottom rails extending into said channel-shaped upright stile between and fitting snugly against said opposed bearing strips so that said rail forms a further reinforcement for opposite sides of said channel-shaped stile, a frame within the space between said top and intermediate rails, said frame having an upright inwardly opening channel-shaped side rail, and provided at the upper and lower ends of said side rail with top and bottom substantially horizontal rails, the base of said side rail being interlocked with the inner edges of said inwardly opening channel-shaped stile, means securing said frame to said stile, including transversely extending members within said channel-shaped stile and having their opposite upright edges within the grooves aforesaid in said bearing strips, clamping elements extending through the base aforesaid of said channel-shaped side rail and engaging said transversely extending members, opposite sides of the top rail of said door projecting downwardly beyond the bottom edge thereof and forming therewith a downwardly opening groove, opposite sides of the intermediate rail of said door projecting upwardly beyond the upper edge thereof and forming therewith an upwardly opening groove, the top rail of said frame having spaced

upwardly projecting ribs fitting into said downwardly opening groove and preventing relative horizontal movement between the top rails respectively of said door and of said frame, the bottom rail of said frame having spaced downwardly projecting ribs fitting into said upwardly opening groove and preventing relative horizontal movement between the intermediate rail of said door and the bottom rail of said frame, and means holding the spaced projections aforesaid against displacement, including fastening elements respectively extending through the top and bottom rails of said frame and engaging the adjacent edges of said top and intermediate rails of said door.

5. A metal door structure comprising an inwardly opening channel-shaped upright stile, the inner faces of opposite sides of said channel-shaped stile being provided adjacent the mouth and adjacent the base of the channel with opposed integral bearing strips, each of the opposed strips adjacent the mouth of said channel having an inwardly opening groove therein, top and bottom horizontal rails extending into said channel-shaped upright stile between and fitting snugly against said opposed bearing strips so that said rails form reinforcements for opposite sides of said channel-shaped stile, a horizontal rail intermediate said top and bottom rails and extending into said channel-shaped upright stile between and fitting snugly against said opposed bearing strips so that said rail forms a further reinforcement for opposite sides of said channel-shaped stile, a frame within the space between said top and intermediate rails, said frame having an upright inwardly opening channel-shaped side rail, and provided at the upper and lower ends of said side rail with top and bottom substantially horizontal rails, the base of said side rail being interlocked with the inner edges of said inwardly opening channel-shaped stile, means securing said frame to said stile, including transversely extending members within said channel-shaped stile and having their opposite upright edges within the grooves aforesaid in said bearing strips, clamping elements extending through the base aforesaid of said channel-shaped side rail and engaging said transversely extending members, the bottom edge of the top rail of said door being provided with a downwardly opening groove, the upper edge of the intermediate rail of said door being provided with an upwardly opening groove, the top rail of said frame having spaced upwardly projecting ribs fitting into said downwardly opening groove and preventing relative horizontal movement between the top rails respectively of said door and said frame, the bottom rail of said frame having spaced downwardly projecting ribs fitting into said upwardly opening groove and preventing relative horizontal movement between the intermediate rail of said door and the bottom rail of said frame, and means holding the spaced projections aforesaid against displacement, including fasteners respectively extending through the top and bottom rails of said frame and engaging the adjacent edges of said top and intermediate rails of said door.

6. A metal door structure comprising an inwardly opening channel-shaped upright stile, a horizontal rail extending into said channel-shaped upright stile between and fitting snugly against opposite sides thereof so that said rail forms a reinforcement for opposite sides of said channel-shaped stile, a horizontal web within and connected to opposite sides of said rail intermediate the upper and lower edges thereof, and an upwardly opening expander member of U-cross section within said rail and cooperating with said web to form a substantially box-like reinforcement for said rail, the lower edge of said rail being at the lower end of said stile, and the base of said U-shaped expander member being at the lower edge of said rail and having means for holding a weather-strip engageable with a threshold.

7. A metal door structure comprising an inwardly opening channel-shaped upright stile, the inner faces of opposite sides of said channel-shaped stile being provided adjacent the mouth and adjacent the base of the channel

with opposed integral bearing strips, each of the opposed strips adjacent the mouth of said channel having an inwardly opening groove therein, top and bottom horizontal rails extending into said channel-shaped upright stile between and fitting snugly against said opposed bearing strips so that said rails form reinforcements for opposite sides of said channel-shaped stile, a horizontal rail intermediate said top and bottom rails and extending into said channel-shaped upright stile between and fitting snugly against said opposed bearing strips so that said rail forms a further reinforcement for opposite sides of said channel-shaped stile, a frame within the space between said top and intermediate rails, said frame having an upright inwardly opening channel-shaped side rail, opposite sides of the channel-shaped side rail of said frame having flanges respectively for holding a weather-strip and a screen frame, the base of said side rail being interlocked with the inner edges of said inwardly opening channel-shaped stile, means securing said frame to said stile including members within said channel-shaped stile and engaging the grooves aforesaid in said bearing strips, and means extending through the base aforesaid of said channel-shaped side rail and engaging said members.

8. A metal door structure comprising an inwardly opening channel-shaped upright stile, the inner faces of opposite sides of said channel-shaped stile being provided adjacent the mouth and adjacent the base of the channel with opposed integral bearing strips, each of the opposed strips adjacent the mouth of said channel having an inwardly opening groove therein, top and bottom horizontal rails extending into said channel-shaped upright stile between and fitting snugly against said opposed bearing strips so that said rails form reinforcements for opposite sides of said channel-shaped stile, a horizontal rail intermediate said top and bottom rails and extending into said channel-shaped upright stile between and fitting snugly against said opposed bearing strips so that said rail forms a further reinforcement for opposite sides of said channel-shaped stile, a horizontal rail intermediate said top and bottom rails extending into said channel-shaped upright stile between and fitting snugly against said opposed bearing strips so that said rail forms a further reinforcement for opposite sides of said channel-shaped stile, opposed edges respectively of said bottom rail and of said intermediate rail having oppositely projecting opposed vertically opening channel portions, a kick plate closing the space between said bottom and intermediate rails and having its upper and lower edges within said opposed vertically extending channel portions, a plate-like member closing the mouth of said channel-shaped stile between said bottom and intermediate rails, said plate-like member having portions within the grooves aforesaid in said bearing strips and having an inwardly projecting outwardly opening channel portion receiving the adjacent upright edge of said kick plate, a horizontal web within and connected to opposite sides of said bottom rail intermediate the upper and lower edges thereof, and an upwardly opening expander member of U-cross section within said bottom rail and cooperating with said web to form a substantially box-like reinforcement for said bottom rail, the lower edge of said bottom rail being at the lower end of said stile, and the base of said U-shaped expander member being at the lower edge of said bottom rail and having means for holding a weather-strip engageable with a threshold.
